UNITED STATES PATENT OFFICE.

ALFRED J. JARMAN, OF NEW YORK, N. Y., ASSIGNOR OF ONE-HALF TO JOHN F. WICKENS, OF NEW YORK, N. Y.

PROCESS FOR MAKING PRINTING BLOCKS AND STAMPS.

1,000,916.

Specification of Letters Patent. Patented Aug. 15, 1911.

No Drawing.

Application filed October 3, 1910. Serial No. 584,956.

To all whom it may concern:

Be it known that I, ALFRED J. JARMAN, a subject of the King of England, and a resident of the city of New York, borough of 5 Manhattan, in the county and State of New York, have invented a new and Improved Process for Making Printing Blocks and Stamps, of which the following is a full, clear, and exact description.

10 The invention relates to the process of making printing blocks and stamps from photographic negatives by the use of a specially prepared printing paper, a mold, and a die from which a bas-relief can be obtained, and an object of the invention is to provide an expeditious and economical process whereby innumerable representations of a photograph can be quickly reproduced.

To accomplish the desired result a suitable 20 negative is obtained by the use of a screen, as employed in half-tone work with approximately fifty lines to the inch. Paper of a desired quality is then coated with a preparation consisting of gelatin and sugar with 25 a small quantity of soap mixed therein. This preparation may be impregnated with coloring matter if desired, and preferably consisting of China ink or sugar that has been charred by means of sulfuric acid or 30 the like. After the mentioned preparation has been suitably affixed to the paper and dried the paper is made sensitive to light by immersing the same in a cold solution of potassium bichromate of a strength proportionate to the negative to be employed in 35 the process. The paper is now thoroughly dried in a room free from all actinic light and is then exposed under the mentioned negative in the usual manner until an image 40 of sufficient density is formed, after which the paper is plunged into cold water and thoroughly saturated. After being saturated, the paper is pressed onto a plate of 45 metal or glass, preferably opal glass, which has been previously coated with gelatin, and after becoming sufficiently dry, treated with a five or six per cent. solution of formaldehyde so as to make the gelatin coating partially insoluble, and the said paper is suitably secured to the plate by the use of a 50 squeegee. The prepared plate having the paper attached thereto is now placed in a tray of warm water to which a trace of soap 55 has been added, and in a few moments the gelatin dissolves and the paper is carefully

removed from the plate leaving the gelatin upon the plate. The use of soap in the water materially aids in the rapid and efficient dissolution of the gelatin as the alkali which is contained in the soap has a direct 60 action upon the unaffected parts of the gelatin while not affecting the gelatin which has been acted upon by the light. The gelatin plate with the image thereon is now washed in a soapy water to remove all superfluous 65 matter and then dried without being treated with a hardening solution. After being allowed to dry the image on the plate will appear in considerable relief as will be 70 readily understood. This plate is now 75 placed in cold water and permitted to soak, after which it is transferred to a tray of formalin of a five or six per cent. solution and then surface dried and coated with a mixture of castor oil, linseed oil and spirits 80 of turpentine in approximately equal parts. Any excess of oil is removed from the newly coated surface of the plate, it is carefully wiped clean and is then placed into a metal frame preparatory to obtaining a mold of 85 the image on the plate. A mixture of plumbago, gypsum and water or Portland cement and water with a quantity of talcum powder added to the first mixture, is then provided and poured into the frame to cover the 90 image on the plate and constituting a mold. After the mold has become sufficiently dry the plate is removed therefrom and a representation of the image on the plate will be disclosed in the mold. By employing rubber 95 or celluloid and a vulcanizing press for heating the mold, the rubber or celluloid can be easily pressed into the image disclosed in the mold and a bas-relief of the image will be formed on the rubber or celluloid thus 100 providing the printing stamp or block required.

When the mold is made of the mentioned plumbago and gypsum mixture the desired 105 stamps are made by using soft or vulcanizing rubber and when it is desired to provide hard rubber or celluloid printing stamps a metal mold is constructed.

The presence of soap in the gelatin facilitates very much the separation of the mold 105 from the gelatin plate, this mold being afterward used in a vulcanizing press for making the rubber stamp. By reason of the fact that the bichromated plate was printed through a negative obtained through a 110

screen, it will be seen that the bichromated plate after development presents a surface which is made up of an innumerable quantity of minute projections resulting from the ruling on the screen; it has been a difficult matter to make a mold which may be easily separated from the gelatin plate and still present all of the aforesaid projections, since in the step of separating the mold from the plate more or less of these projections are destroyed because of the mold sticking, with the consequent poor results to be obtained from the rubber stamp when the ink was spread thereon. I have found that the presence of soap as a constituent of the gelatinized plate has a very beneficial effect in aiding the separation of the mold from the plate without damage to any of the projections previously mentioned.

To make a metal mold the gelatin image is treated as mentioned heretofore except that the same is not covered with the castor oil, linseed oil and spirits of turpentine mixture, and the said image is placed in a strong solution of protosulfate of iron or hydroquinon, after which the same is washed in clean water and then placed in a solution of nitrate of silver or chlorid of gold, which in turn will cause a deposit of metal both upon and in the body of the gelatin image, thus thoroughly impregnating the same with the metal. This operation is repeated until the image is absolutely covered by a deposit of metal and the image is then surface dried and placed into an electrotyping bath of sulfate of copper, which will cause a deposit

of copper to form on the plate after which a metal back plate is soldered to the copper deposit to increase the metal thickness.

As mentioned heretofore by employing hard rubber or celluloid an impression of the image on the plate can be easily conveyed to the rubber or celluloid, it being understood that these substances are preferably adapted for the particular use mentioned.

Having thus described my invention, I claim as new and desire to secure by Letters Patent:

The herein-described method for producing printing blocks and stamps from photographic negatives which consists in making a print from a screen negative on suitable material covered with bichromated gelatin having soap incorporated therein, transferring the said gelatin coating with the soap therein from the said material onto a suitable plate and working the same to disclose the image thereon in relief, making an imprint of the said image in a plastic mass consisting of a mixture of plumbago and cement, whereby to form a mold, and then placing the mold in contact with suitable material in a press whereby a stamp or printing block is obtained.

In testimony whereof I have signed my name to this specification in the presence of two subscribing witnesses.

ALFRED J. JARMAN.
